(57) **CLAIM**

The ornamental design for the hemorrhoid treatment device, as shown and described.

DESCRIPTION

FIG. 1 is a top plan view of the hemorrhoid treatment device showing my design.

FIG. 2 is a front view thereof;

FIG. 3 is a side view thereof, an opposite side view being a mirror image thereof; and

FIG. 4 is a back view thereof; and,

FIG. 5 is a bottom plan view thereof.

The broken lines shown in the drawings represent environment and form no part of the claimed design.
